CLAIM

The ornamental design for a tablet computer, as shown and described.

DESCRIPTION

FIG. 1 is a front perspective view of a tablet computer showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of portions of the tablet computer in FIGS. 1-2, 4 and 6 depicts portions of the tablet computer that form no part of the claimed design. The oblique line shading shown in FIGS. 1 and 2 depicts a transparent surface.

1 Claim, 4 Drawing Sheets
